UNITED STATES PATENT OFFICE.

ALEXANDER F. WARD, OF DETROIT, MICHIGAN.

HOOP-PLANING MACHINE.

SPECIFICATION forming part of Letters Patent No. 332,124, dated December 8, 1885.

Application filed April 15, 1885. Serial No. 162,300. (No model.)

To all whom it may concern:

Be it known that I, ALEXANDER F. WARD, of Detroit, in the county of Wayne and State of Michigan, have invented new and useful 5 Improvements in Hoop-Planing Machines; and I do hereby declare that the following is a full, clear, and exact description thereof, reference being had to the accompanying drawings, which form a part of this specification.

10 This invention relates to a new and useful improvement in hoop-planing machines; and the invention consists in the novel construction and arrangement of a self-adjusting pressure-foot, and in an improved construction of 15 the bed, all as hereinafter described.

Figure 1 is a diagram plan of a hoop-planing machine with the pressure-feet removed, but shown in dotted lines. Fig. 2 is a vertical central section on line xx in Fig. 1. Fig. 3 is 20 a cross-section on line yy , Fig. 2. Fig. 4 is a detailed perspective of one of the pressure-feet with its self-adjusting toe removed and shown in dotted lines. Fig. 5 is a diagram showing the self-adjusting toe of the pressure- 25 foot in end view and bearing upon a hoop.

In the accompanying drawings, which form a part of this specification, my invention is illustrated on a hoop-planing machine of the usual style, and arranged to plane two hoops 30 at a time.

A A are the planer-heads. B B are the upper feed-rolls. C C are the lower feed-rolls. D is the front end of the bed, through which the hoops are fed, and which is provided 35 with the usual guides for two hoops. E is that part of the bed between the feed-rolls. F are the pressure-feet, pivotally secured to the standards G, and arranged to press the hoops by their weight onto the bed E immediately 40 in front of the planer-heads.

The parts to which the improvements refer are constructed as follows: H is a toe, provided with a round shank, a, which fits loosely into a socket, b, in the forward end of 45 the pressure-foot. c is a threaded portion on the end of the shank, by means of which the toe is secured to the pressure-foot by a nut, d. e is a pin on the base of the toe, and f is a notch cut in the end of the pressure- 50 foot. The face of the toe is slightly concave in cross-section. In practice the toe is only loosely secured to the pressure-foot, which

allows it to roll in its socket to the necessary degree, as the notch f is cut longer than the pin e, which latter engages into the notch. As it is the toe of the pressure-foot which touches the hoop and bears down upon it, it will be seen that the loose toe adjusts itself to the top side of the hoop and bears upon both edges no matter whether the hoop has the proper bevel or not. Heretofore this toe was formed as an integral part of the pressure-foot and when, as it frequently happened, a hoop blank has not the proper bevel the pressure foot only bore on the edge of the hoop, and the probability was that the hoop touched the bed only on one edge, instead of being pressed down tightly and flatly onto it, as is necessary to form a perfect hoop. It must be considered in connection with this matter that the upper feed-rolls are conical, so as to fit a hoop of proper bevel, and as soon as a hoop of different bevel or no bevel at all is fed it will be compressed on one edge, and this compression always results in giving the hoop a slight twist, which, if not counteracted by the pressure-foot, lifts one edge of the hoop off the bed, and the planer head will form an imperfect hoop of it.

A further improvement of the machine consists in the peculiar construction of the bed E. This is provided, as shown in Fig. 1, with flanges g, by means of which and suitable bolts it is removably and adjustably secured to the under side of the frame, so that it can be adjusted or removed without disturbing or removing any other part of the machine. This bed is provided on its top face with undercut recesses h, filled with Babbitt-metal firmly hammered in and face off, so as to form a level bearing. Experience has shown that such a bearing lasts longer than even steel, and is easily renewed again when worn out.

What I claim as my invention is—

A pressure-foot provided with a self-adjusting toe and means, such as the recess in the pressure-foot and pin e on the toe, for preventing accidental displacement, substantially as described.

ALEXANDER F. WARD.
